HONE

Harold L. Blood, Worcester, Mass., assignor to
The Heald Machine Company, Worcester,
Mass., a corporation of Massachusetts

Application March 20, 1936, Serial No. 69,861

14 Claims. (Cl. 51—184.2)

The present invention relates to a hone, particularly adapted for the finishing of tapered internal surfaces, as for example, the outer raceways of roller bearings. A modified form of hone, adapted for external surfaces and embodying the same general arrangement of parts, is disclosed in applicant's copending application for a Hone, Serial No. 68,289, filed March 11, 1936.

In prior devices of this character the honing material is generally held rigidly to the shape of the surface being honed. In order to avoid the appearance of scratch marks on the work it is desirable to give the hone a slight axial reciprocation relative to the work, this reciprocation eliminating the circular scratch marks otherwise resulting. With a rigid hone, there can be a reciprocation thereof only where the hone is adapted for cylindrical surfaces. One of the principal objects of the present invention is to provide a hone which will operate on a tapered surface and will also permit a reciprocation of the hone relative to the workpiece.

Attempts have been made to produce a hone having sufficient resiliency to accommodate itself to small variations in workpiece diameter, as, for example, the Stinson Patent No. 1,418,847, dated June 6, 1922. This hone has a conical actuator engageable with the ends of levers for swinging the latter outwardly to urge the honing members against the workpiece. The taper of the cone, for satisfactory operation, is such that a radial pressure inwardly of the honing members will not cause the cone to slide axially to allow the honing members to collapse. The structure is accordingly not applicable to tapered workpieces where the hone is given an axial reciprocation. A further object of the invention is to provide a hone in which the honing members may move inwardly in response to an inward pressure on the members.

The surface finish, as a result of the honing action thereon, is controlled to a great extent by the pressure exerted by the hone against the surface, and the present invention also provides for adjusting the amount of pressure by the individual honing members so that the surface finish, as well as the amount of material removed during the honing action, may be controlled.

Other and further objects and advantages of the invention will appear from the following detailed description taken in connection with the accompanying drawing, in which—

Fig. 1 is a sectional view through a hone embodying the invention.

Fig. 2 is an end view of the hone.

Fig. 3 is a side elevation of one of the elements of the hone.

Like reference characters refer to like parts in the different figures.

Referring first to Fig. 1, the honing device 1

is intended to operate upon the tapered surface 2 of a workpiece *a*, mounted for rotation in any suitable workholder 3 which may have the form of any well-known chuck in which the workpiece is mounted for rotation about an axis concentric to the surface being honed. The honing device is preferably mounted on a machine having a reciprocatory table, such as the usual Heald grinding machine, one example of which is disclosed in the Guild Patent No. 1,971,138, dated Aug. 21, 1934. Either the device 1 or the chuck 3 is mounted on the reciprocatory table and the reciprocations of the latter serve to procure a short reciprocation of the hone relative to the workpiece and axially thereof. The table also provides for withdrawal of the hone from within the bore of the workpiece and for returning the hone to operative position within the workpiece bore for a honing operation thereon. The machine arrangements by which the various movements of the hone relative to the workpiece are procured are not a part of the present invention and need not be described in detail. It is sufficient to note that the honing device is mounted in a bracket 4 carried alternatively by the table or the base, the chuck in either event being mounted on the other machine element to provide for the relative reciprocation between the honing device and the workpiece.

The device of the invention comprises a sleeve 5, having a cylindrical end portion 6 corresponding in diameter to a horizontal bore 7 in the bracket 4, and in which it is positioned, being locked therein by a set screw 8 in the bracket. A shoulder 9 on the member 5 engages the end 35 of the bracket 4. The sleeve 5 at its opposite end has an enlarged arbor or head 10 having a tapered end portion 11. The head is provided with a plurality of radial slots 12 extending substantially the entire length of the head, and each slot has positioned therein a bell crank lever 13, Fig. 1. A ring 14 which fits over the rearward end of the head 10 and is freely turnable thereon, has an arcuate annular groove 15 therein in which one end of each of the bell crank levers 13 is positioned. The ring has an inwardly extending flange 16 engaging with the shoulder 17 provided by the head, thereby holding said ring in position. The levers are supported by said ring for rocking movement within the slots in which the levers are positioned, this rocking movement being about an axis adjacent to the outer end of each lever, the latter being arcuate to correspond to the shape of the grooves 15 engaged thereby. The connection between each of the levers and the arbor is thus a free pivotal connection making the levers readily removable from the arbor at any time.

Adjacent the opposite end of each bell crank lever is positioned an arcuate projection 18 which 60

engages with a correspondingly shaped recess 19 in a holder 20. The latter has attached to the outer side thereof a bar 21 of suitable honing material which may be formed, for example, from abrasive material. The bar 21 is suitably secured to the holder 20, as by glue, or any other desired securing means. The connection between each lever and the associated holder is also a free pivotal connection, making it possible to separate the holder from its supporting lever at any time.

Coil springs 22 and 23, each arranged in the form of an annulus, extend around the head outside of the holders 20 and engage in notches 24 and 25 at opposite ends of each of the holders respectively. Said springs normally tend to move the holders 20 inwardly to move the honing material out of operative position and also keep the holders 20 against the projections 18 of the bell crank levers. Small notches 25' are provided in the tapered end of the head 10 to receive the spring 22 when the holders 20 are removed from the device. A small coil spring 27, positioned in a recess 28 in each of the bell crank levers, engages with the corresponding holder 20 rearwardly of the recess 19 for procuring a turning movement of the holder about its pivotal support. The spring 27 urges the forward end of the holder 20 inwardly so that the device may readily enter the tapered bore of the workpiece when being moved into operative position.

For holding the honing members in operative position during honing, the sleeve 5 has a plunger 29 slidably therein, the end of said plunger engaging with all of the bell crank levers at the corners thereof. The plunger has no rigid connection with the levers and thus, by reason of the free connection, the levers can readily be removed from the arbor without the necessity for the removal of any connecting elements. It will be noted that all of the pivots of the lever, that is to say, the connection between the lever and the arbor, the connection between the lever and the holder 20, and the connection between the lever and the plunger, are all free pivotal connections, making the substitution of one lever for another a very simple procedure. A coil spring 30 is positioned within the sleeve 5 and surrounds an integral stem 31 extending from the plunger, being located between said plunger and a threaded plug 32 engaging in the end of the sleeve 5. The plug 32, being threaded, is adjustable within the sleeve for varying the tension on the spring 30. The stem 31 from the plunger extends 55 through an opening 33 centrally of the plug 32 and has adjustable nuts 34 on the threaded end thereof. These nuts 34, by engagement with the end of the plug, control the extent of movement of the plunger to the left and thereby control or 60 limit the outward movement of the honing members. The pressure exerted on the levers 13 by the plunger 29 is axial and the plunger is so located that an inward pressure on the honing members will cause an inward swinging movement of the levers against the pressure of the plunger. The honing members may thus engage 65 with a tapered surface even if there is a relative reciprocation between the work and the hone.

The arrangement disclosed provides for the 70 substitution of one type of honing member for another merely by the removal of the holders 20 with the honing material attached thereto and the substitution of other holders. This is done by slipping the springs 22 and 23 out of the notches 75 in the holders 20 thereby releasing the holders,

the spring 22 being then held on the head by the notches 25'. The spring 23 when removed from holding engagement with the holders 20 still surrounds the head of the sleeve 5 and prevents the several levers 13 from dropping out of the 5 head. Since none of the levers 13 is permanently fastened within the device, it will also be apparent that these levers are readily interchanged in adapting the device to different sizes of workpieces by reason of the free pivotal connections 10 between the levers and the associated elements. The device is moreover adjustable to different size workpieces by changing the position of the nuts 34, thereby varying the position of the plunger 29. The amount of pressure exerted by 15 the honing members on the workpiece is also adjustable by changing the position of the plug 32 on the sleeve 5, adjustment of this plug also controlling the operative position of the hones.

In operation, assuming the device to have been 20 axially withdrawn from the workpiece by the table movement above referred to, the small springs 27 have urged the holders 20 about the pivotal support thereof so that said holders assume a position of maximum taper to assure 25 entry of the device within the bore of the workpiece. The springs 22 and 23 keep the holders 20 in engagement with the bell crank levers, and as the honing device moves to the left, Fig. 1, relative to the workpiece, the honing members 30 engage with the workpiece and are rocked about their pivotal supports to the position of Fig. 1, thereby engaging the tapered surface over its entire width. When the device is in the position of Fig. 1, in readiness for honing, it may be given 35 a slight reciprocatory movement without affecting the honing operation, since, as the device moves farther to the left from the position shown, the honing members move inwardly against the pressure of the spring 30, rocking the bell crank 40 levers about their pivotal supports. Upon movement of the table to the right during the slight reciprocation, the spring 30 urges the hones outwardly and holds them in engagement with the workpiece. With the device adjusted as in Fig. 45 1, the relative position of these parts in this figure must represent the right hand end of the short reciprocatory movement (assuming the honing device to be the reciprocated element) as will be apparent. The honing members are 50 thus held in engagement with the workpiece at all times during the axial reciprocation of the hone relative to the workpiece, even though the surface being honed is tapered. The plunger and associated mechanism may be said to be reversible since the honing members if pressed inwardly will procure a retraction of the plunger for a contraction of the hone, with the plunger normally holding the honing members in expanded position.

I claim:

1. In a honing device, an arbor, a lever carried thereby and rockable relative thereto, a honing member on said lever, interconnecting means on said member and lever providing for 65 rocking of the member relative to the lever about an axis substantially at right angles to the axis of the arbor, means engageable with said lever for urging the lever and the member thereon into operative position, and resilient means between 70 said lever and member for procuring a turning movement of said member relative to the lever to a predetermined position.

2. In a honing device, a support, a lever carried thereby and pivoted thereon, a honing mem- 75

ber, interconnecting means on said member and lever providing a free pivotal connection for rocking of the member relative to the lever about the axis substantially at right angles to the axis of the support and means releasably attaching the member to said lever, including resilient means for holding the member and lever in engagement.

3. In a honing device, a support, a lever carried thereby and pivotally mounted thereon, a honing member carried by the lever, and means releasably attaching the member to said lever, said means including an arcuate protuberance and a cooperating arcuate recess on the member and lever to provide a free pivotal connection between the member and lever, and resilient means for holding the protuberance and recess in interengagement.

4. In a honing device, a support, a lever carried thereby and pivotally mounted thereon, a honing member carried by the lever, and means releasably attaching the member to said lever, said means including an arcuate protuberance and a cooperating arcuate recess on the member and lever to provide a free pivotal connection between the member and lever and a spring for holding said cooperating protuberance and recess in engagement.

5. In a honing device, an arbor having a radial slot at one end thereof, a lever positioned in said slot and having a pivotal movement relative to the arbor, a honing member rockably mounted on said lever, and a spring surrounding the arbor and engaging with the honing member for holding the latter in engagement with the lever.

6. In a honing device, an arbor having a plurality of radial slots therein, a lever positioned in each of said slots and having a pivotal movement relative to the arbor, a honing member rockably mounted on each of said levers, resilient means engaging with said levers for urging the honing members into operative position, and other resilient means engaging with the honing members for holding the latter in engagement with the levers.

7. In a honing device, an arbor having a plurality of radial slots at one end thereof, a lever positioned in each of said slots each lever having an arcuate surface engageable with a part of the arbor for rocking movement relative thereto, a honing member rockably mounted on each of said levers, a plunger slidable in the arbor and engageable with each of said levers, a spring in said arbor engaging with the plunger, and means for adjusting the position of the spring for controlling the expanded position of the honing members.

8. In a honing device, an arbor having a plurality of radial slots at one end thereof, a lever positioned in each of said slots, a ring engaging all of said levers at one end thereof and providing a pivotal support therefor, a honing member rockably mounted on each of said levers, springs holding said members in position on said levers, a plunger within the arbor and engaging with each of said levers, and a spring in said arbor for urging the plunger against the levers to move the latter outwardly.

9. In a honing device, an arbor having a plurality of radial slots at one end thereof, a lever positioned in each of said slots, a ring engaging all of said levers at one end thereof and providing

a pivotal support therefor, a honing member rockably mounted on each of said levers, springs holding said members in position on said levers, a plunger within the arbor and engaging with each of said levers, a spring in said arbor for urging the plunger against the levers to move the latter outwardly, and means for adjusting the extent of movement of the plunger for controlling the expanded position of the honing members.

10. In a honing device, an arbor having a radial slot at one end thereof, a lever removably positioned in said slot and turnable about one end thereof for pivotal movement relative to the arbor, said lever being supported by the arbor against lateral movement, a honing member rockably mounted on said lever, a plunger axially slidable in the arbor and engageable with the lever for urging the honing member thereon into operative position, and a spring in said arbor for engagement with the plunger.

11. In a honing device, an arbor having a radial slot at one end thereof, a lever removably positioned in said slot and turnable about one end thereof for pivotal movement relative to the arbor, said lever being supported by the arbor against lateral movement, a honing member rockably mounted on said lever, a plunger axially slidable in the arbor and engageable with the lever for urging the honing member thereon into operative position, a spring in said arbor for engagement with the plunger, and means for adjusting the extent of movement of the plunger for controlling the operative position of the honing member.

12. In a honing device, an arbor, a lever carried thereby and turnable relative thereto about an axis out of parallel relation to the axis of the arbor, a honing member carried by the lever, and resilient means within the arbor and engaging with said lever at a point spaced from its axis of rotation relative to the arbor, said resilient means including a member movable axially of the arbor and engageable with said lever for urging said lever and the honing member carried thereby into operative position.

13. In a honing device, an arbor, a radial slot at one end thereof, a lever removably positioned in said slot and having a free pivotal connection at one end thereof with the arbor, said lever being supported by the arbor against lateral movement, a honing member rockably mounted on the lever, a plunger axially slidable in the arbor and engageable with the lever for urging the honing member thereon into operative position, the lever and plunger being free of positive interconnection, whereby the lever is removable at any time from the arbor.

14. In a honing device, an arbor having a radial slot at one end thereof, a lever removably positioned in said slot and having a free pivotal connection at one end thereof with the arbor, said lever being supported by the arbor against lateral movement, a honing member having a free pivotal connection with said lever, a plunger axially slidable in the arbor and engageable with the lever for urging the lever and the honing member thereon into operative position, said lever being free of positive connection to the plunger to provide for removal of the lever from the arbor at any time.

HAROLD L. BLOOD.
